TOTE TRAY

George Payne, Bedford Hills, N.Y., assignor to American Standard Inc., New York, N.Y.

Filed Sept. 25, 1972, Ser. No. 291,870

Term of patent 14 years

Int. Cl. D3—99

U.S. Cl. D87—1 R

FIG. 1

FIG. 2

FIG. 5

FIG. 3

FIG. 6

FIG. 4

FIG. 1 is a top front perspective view of a tote tray embodying my new design;

FIG. 2 is a bottom rear perspective view thereof;

FIG. 3 is a top plan view thereof;

FIG. 4 is a cross-sectional view thereof, taken along the lines 4-4 of FIG. 1;

FIG. 5 is a cross-sectional view thereof, taken along the lines 5-5 of FIG. 1; and

FIG. 6 is a side elevational view thereof, taken from the position 6-6 of FIG. 1.

I claim:

The ornamental design for a tote tray, substantially as shown.
